TEETHING DEVICE

Marshall F. Newmark, Spring Valley, Calif., assignor to
Progressive Products, Inc., a corporation of California

Application March 27, 1953, Serial No. 24,220

Term of patent 14 years

(Cl. D83—11)

FIG. 1

FIG. 2

FIG. 4

FIG. 2

FIG. 5

To all whom it may concern:

Be it known that I, Marshall F. Newmark, a citizen of the United States, residing at Spring Valley, in the county of San Diego and State of California, have invented a new, original, and ornamental Design for a Teething Device, of which the following is a specification, reference being had to the accompanying drawing, constituting a part thereof:

In the drawing:

Figure 1 is a perspective view of a teething device showing my new design;

Figure 2 is a sectional view taken on the line II—II of Figure 1;

Figure 3 is a sectional view taken on the line III—III of Figure 1;

Figure 4 is a sectional view taken on the line IV—IV of Figure 1; and

Figure 5 is a perspective view of the teething device which has been turned about 90° from the position of Figure 1.

I claim:

The ornamental design for a teething device, substantially as shown.
